(57) **ABSTRACT**

A scan driving circuit is disclosed and used to execute a driving operation for cascaded scan lines. The scan driving circuit has a pull-down control module, a pull-down module, a pull-up module, a pull-up maintaining module, a bootstrap capacitor, a constant low-level voltage source and a constant high-level voltage source; the scan driving circuit uses a PMOS type transistor to control the pull-down control module, the pull-down module, the pull-up module and the pull-up maintaining module. The scan driving circuit has a simple overall structure and lower energy consumption.

SCAN DRIVING CIRCUIT

FIELD OF THE INVENTION

The present invention relates to a field of display driving, and more particularly to a scan driving circuit.

BACKGROUND OF THE INVENTION

A gate driver on array (GOA) generates a scan driver circuit on an existing array substrate of a thin film transistor liquid crystal display (TFT-LCD) in order to implement a driving method which progressively scans for scan lines. A structural diagram of an existing scan driving circuit is illustrated in FIG. 1, and the scan driving circuit 10 includes a pull-up control module 101, a pull-up module 102, a down-stream module 103, a pull-down module 104, a bootstrap capacitor 105, and a pull-down maintaining module 106.

The scan driving circuit generally uses an N-Metal-Oxide-Semiconductor (NMOS) type transistor. However, for the production of the NMOS transistor, the production cost of a photomask which is used in a photolithography process is higher. Moreover, the overall circuit structure of the scan driving circuit is more complex so as to consume more energy.

As a result, it is necessary to provide a scan driving circuit to solve the problem existing in the conventional technologies.

SUMMARY OF THE INVENTION

A primary object of the present invention is to provide a scan driving circuit that has a simple structure and lower energy consumption, so as to solve the problem of an existing scan driving circuit which has a complex structure and higher energy consumption.

To solve the above problems, the technical solution of the present invention is as follows:

A scan driving circuit is provided in an embodiment of the present invention, the scan driving circuit is used to execute a driving operation for cascaded scan lines, and comprises:

a pull-down control module receiving a previous-level scan signal, and generating a low-level scan level signal corresponding to one of the scan lines according to the previous-level scan signal;

a pull-down module pulling down a scan signal of the corresponding scan line according to the scan level signal and a first clock signal;

a pull-up module pulling up the scan signal of the corresponding scan line according to a low-level signal and a high-level signal;

a pull-up maintaining module keeping the scan level signal of the corresponding scan line in a high-level according to the low-level signal and the high-level signal;

a bootstrap capacitor generating a low-level or a high-level of the scan level signal of the scan line;

a constant low-level voltage source providing the low-level signal; and

a constant high-level voltage source providing the high-level signal;

wherein the scan driving circuit uses a P-metal-oxide-semiconductor (PMOS) type transistor to control the pull-down control module, the pull-down module, the pull-up module and the pull-up maintaining module;

wherein the pull-down control module includes a first switch transistor, a control end of the first switch transistor

2

inputs the previous-level scan signal, an input end of the first switch transistor inputs a low-level scan signal, and an output end of the first switch transistor is connected to the pull-down module, the pull-up maintaining module and the bootstrap capacitor respectively;

wherein the pull-up maintaining module includes a second electrical potential maintaining capacitor, one end of the second electrical potential maintaining capacitor is connected to the constant high-level voltage source, and the other end of the second electrical potential maintaining capacitor is connected to the output end of the first switch transistor.

In the scan driving circuit of the present invention, the pull-down module comprises a second switch transistor, a control end of the second switch transistor is connected to the output end of the first switch transistor of the pull-down control module, an input end of the second switch transistor inputs a first clock signal, and an output end of the second switch transistor inputs a present-level scan signal.

In the scan driving circuit of the present invention, the pull-up module comprises a third switch transistor, a control end of the third switch transistor is connected to the constant low-level voltage source, an input end of the third switch transistor is connected to the constant high-level voltage source, and an output end of the third switch transistor is connected to the output end of the second switch transistor.

In the scan driving circuit of the present invention, the pull-up maintaining module further comprises a fourth switch transistor, a fifth switch transistor, a sixth switch transistor and a seventh switch transistor,

wherein a control end of the fourth switch transistor is connected to the input end of the second switch transistor, an input end of the fourth switch transistor is connected to an output end of the fifth switch transistor, and an output end of the fourth switch transistor is connected to the output end of the first switch transistor;

wherein a control end of the fifth switch transistor is connected to an output end of the seventh switch transistor, and an input end of the fifth switch transistor is connected to the constant high-level voltage source;

wherein a control end of the sixth switch transistor is connected to the output end of the first switch transistor, an input end of the sixth switch transistor is connected to the constant high-level voltage source, and an output end of the sixth switch transistor is connected to an output end of the seventh switch transistor;

wherein a control end of the seventh switch transistor inputs a second clock signal, an input end of the seventh switch transistor is connected to the constant low-level voltage source, and the output end of the seventh switch transistor is connected to the control end of the third switch transistor.

In the scan driving circuit of the present invention, the second clock signal and the first clock signal are reverse clock impulse signals.

In the scan driving circuit of the present invention, the pull-down control module further comprises a eighth switch transistor, a control end of the eighth switch transistor inputs a next-level scan signal, an input end of the eighth switch transistor inputs a low-level scan signal, and an output end of the eighth switch transistor is connected to the pull-down module, the pull-up maintaining module and the bootstrap capacitor respectively.

In the scan driving circuit of the present invention, the pull-up maintaining module further comprises a first electrical potential maintaining capacitor, one end of the first electrical potential maintaining capacitor is connected to the

constant high-level voltage source, and the other end of the first electrical potential maintaining capacitor is connected to the output end of the seventh switch transistor.

In the scan driving circuit of the present invention, the pull-down control module comprises a first switch transistor and a ninth switch transistor;

wherein the control end of the first switch transistor inputs a low-level scan signal, the input end of the first switch transistor inputs the previous-level scan signal, and the output end of the first switch transistor is connected to an input end of the ninth switch transistor;

wherein a control end of the ninth switch transistor inputs a second clock signal, and an output end of the ninth switch transistor is connected to the pull-down module, the pull-up maintaining module and the bootstrap capacitor respectively.

In the scan driving circuit of the present invention, the second clock signal and the first clock signal are reverse clock impulse signals.

In the scan driving circuit of the present invention, the pull-down control module further comprises an eighth switch transistor;

wherein a control end of the eighth switch transistor inputs a low-level scan signal, an input end of the eighth switch transistor inputs a next-level scan signal, and an output end of the eighth switch transistor is connected to an input end of the ninth switch transistor.

A scan driving circuit is provided in an embodiment of the present invention, the scan driving circuit is used to execute a driving operation for cascaded scan lines, and comprises:

a pull-down control module receiving a previous-level scan signal, and generating a low-level scan level signal corresponding to one of the scan lines according to the previous-level scan signal;

a pull-down module pulling down a scan signal of the corresponding scan line according to the scan level signal and a first clock signal;

a pull-up module pulling up the scan signal of the corresponding scan line according to a low-level signal and a high-level signal;

a pull-up maintaining module keeping the scan level signal of the corresponding scan line in a high-level according to the low-level signal and the high-level signal;

a bootstrap capacitor generating a low-level or a high-level of the scan level signal of the scan line;

a constant low-level voltage source providing the low-level signal; and

a constant high-level voltage source providing the high-level signal;

wherein the scan driving circuit uses a P-metal-oxide-semiconductor

(PMOS) type transistor to control the pull-down control module, the pull-down module, the pull-up module and the pull-up maintaining module.

In the scan driving circuit of the present invention, the pull-down control module includes a first switch transistor, a control end of the first switch transistor inputs the previous-level scan signal, an input end of the first switch transistor inputs a low-level scan signal, and an output end of the first switch transistor is connected to the pull-down module, the pull-up maintaining module and the bootstrap capacitor respectively.

In the scan driving circuit of the present invention, the pull-down module comprises a second switch transistor, a control end of the second switch transistor is connected to the output end of the first switch transistor of the pull-down control module, an input end of the second switch transistor

inputs a first clock signal, and an output end of the second switch transistor inputs a present-level scan signal.

In the scan driving circuit of the present invention, the pull-up module comprises a third switch transistor, a control end of the third switch transistor is connected to the constant low-level voltage source, an input end of the third switch transistor is connected to the constant high-level voltage source, and an output end of the third switch transistor is connected to the output end of the second switch transistor.

In the scan driving circuit of the present invention, the pull-up maintaining module further comprises a fourth switch transistor, a fifth switch transistor, a sixth switch transistor and a seventh switch transistor;

wherein a control end of the fourth switch transistor is connected to the input end of the second switch transistor, an input end of the fourth switch transistor is connected to an output end of the fifth switch transistor, and an output end of the fourth switch transistor is connected to the output end of the first switch transistor;

wherein a control end of the fifth switch transistor is connected to an output end of the seventh switch transistor, and an input end of the fifth switch transistor is connected to the constant high-level voltage source;

wherein a control end of the sixth switch transistor is connected to the output end of the first switch transistor, an input end of the sixth switch transistor is connected to the constant high-level voltage source, and an output end of the sixth switch transistor is connected to an output end of the seventh switch transistor;

wherein a control end of the seventh switch transistor inputs a second clock signal, an input end of the seventh switch transistor is connected to the constant low-level voltage source, and the output end of the seventh switch transistor is connected to the control end of the third switch transistor;

wherein the second clock signal and the first clock signal are reverse clock impulse signals.

In the scan driving circuit of the present invention, the pull-down control module further comprises an eighth switch transistor, a control end of the eighth switch transistor inputs a next-level scan signal, an input end of the eighth switch transistor inputs a low-level scan signal, and an output end of the eighth switch transistor is connected to the pull-down module, the pull-up maintaining module and the bootstrap capacitor respectively.

In the scan driving circuit of the present invention, the pull-up maintaining module further comprises a first electrical potential maintaining capacitor, one end of the first electrical potential maintaining capacitor is connected to the constant high-level voltage source, and the other end of the first electrical potential maintaining capacitor is connected to the output end of the seventh switch transistor.

In the scan driving circuit of the present invention, the pull-up maintaining module includes a second electrical potential maintaining capacitor, one end of the second electrical potential maintaining capacitor is connected to the constant high-level voltage source, and the other end of the second electrical potential maintaining capacitor is connected to the output end of the first switch transistor.

In the scan driving circuit of the present invention, the pull-down control module comprises a first switch transistor and a ninth switch transistor;

wherein the control end of the first switch transistor inputs a low-level scan signal, the input end of the first switch transistor inputs the previous-level scan signal, and the output end of the first switch transistor is connected to an input end of the ninth switch transistor;

wherein a control end of the ninth switch transistor inputs a second clock signal, and an output end of the ninth switch transistor is connected to the pull-down module, the pull-up maintaining module and the bootstrap capacitor respectively;

wherein the second clock signal and the first clock signal are reverse clock impulse signals.

In the scan driving circuit of the present invention, the pull-down control module further comprises an eighth switch transistor;

wherein a control end of the eighth switch transistor inputs a low-level scan signal, an input end of the eighth switch transistor inputs a next-level scan signal, and an output end of the eighth switch transistor is connected to the input end of the ninth switch transistor.

In contrast to the existing scan driving circuit, the scan driving circuit of the present invention uses a PMOS type transistor to control every module, so as to let the scan driving circuit to have a simple overall structure and lower energy consumption, which solves the problem of the existing scan driving circuit having a complex structure and higher energy consumption.

To allow the above description of the present invention to be more clear and comprehensive, there are preferred embodiments with the accompanying figures described in detail below.

DESCRIPTION OF THE DRAWINGS

FIG. 1 is a structural diagram of an existing scan driving circuit;

FIG. 2 is a structural diagram of a scan driving circuit according to the first preferred embodiment of the present invention;

FIG. 3 is a signal waveform diagram of a scan driving circuit according to the first preferred embodiment of the present invention;

FIG. 4 is a structural diagram of a scan driving circuit according to the second preferred embodiment of the present invention;

FIG. 5 is a structural diagram of a scan driving circuit according to the third preferred embodiment of the present invention; and

FIG. 6 is a structural diagram of a scan driving circuit according to the fourth preferred embodiment of the present invention.

DETAILED DESCRIPTION OF THE PREFERRED EMBODIMENTS

The structure and the technical means adopted by the present invention to achieve the above and other objects can be best understood by referring to the following detailed description of the preferred embodiments and the accompanying drawings. Furthermore, directional terms described by the present invention, such as upper, lower, front, back, left, right, inner, outer, side, longitudinal/vertical, transverse/horizontal, etc., are only directions by referring to the accompanying drawings, and thus the used directional terms are used to describe and understand the present invention, but the present invention is not limited thereto.

In the drawings, units with similar structures are represented with the same label.

Refer to FIG. 2, which is a structural diagram of a scan driving circuit according to the first preferred embodiment of the present invention. The scan driving circuit 20 of the present preferred embodiment is used to execute a driving

operation for cascaded scan lings, and comprises: a pull-down control module 21, a pull-down module 22, a pull-up module 23, a pull-up maintaining module 24, a bootstrap capacitor C1, a constant low-level voltage source and constant high-level voltage source. The pull-down control module 21 is used to receive a previous-level scan signal G(N-1) and generate a low-level scan level signal Q(N) corresponding to one of the scan lines according to the previous-level scan signal G(N-1); the pull-down module 22 is used to pull down a scan signal G(N) of the corresponding scan line according to the scan level signal Q(N) and a first clock signal CK; the pull-up module 23 is used to pull up the scan signal G(N) of the corresponding scan line according to a low-level signal VGL and a high-level signal VGH; the pull-up maintaining module 24 is used to keep the scan level signal Q(N) of the corresponding scan line in a high-level according to the low-level signal VGL and the high-level signal VGH; the bootstrap capacitor C1 is used to generate a low-level or a high-level of the scan level signal Q(N) of the scan line; the constant low-level voltage source is used to provide the low-level signal VGL; and the constant high-level voltage source is used to provide the high-level signal VGH.

The scan driving circuit 20 of the present invention uses a P-metal-oxide-semiconductor (PMOS) type transistor to control the pull-down control module 21, the pull-down module 22, the pull-up module 23 and the pull-up maintaining module 24.

The pull-down control module 21 includes a first switch transistor T1. A control end of the first switch transistor T1 inputs the previous-level scan signal G(N-1), an input end of the first switch transistor T1 inputs a low-level scan signal U2D, and an output end of the first switch transistor T1 is connected to the pull-down module 22, the pull-up maintaining module 23 and the bootstrap capacitor C1 respectively.

The pull-down module 22 comprises a second switch transistor T2. A control end of the second switch transistor T2 is connected to the output end of the first switch transistor T1 of the pull-down control module 21, an input end of the second switch transistor T2 inputs a first clock signal CK, and an output end of the second switch transistor T2 inputs a present-level scan signal G(N).

The pull-up module 23 comprises a third switch transistor T3. A control end of the third switch transistor T3 is connected to the constant low-level voltage source, an input end of the third switch transistor T3 is connected to the constant high-level voltage source, and an output end of the third switch transistor T3 is connected to the output end of the second switch transistor T2.

The pull-up maintaining module 24 further comprises a fourth switch transistor T4, a fifth switch transistor T5, a sixth switch transistor T6, a seventh switch transistor T7 and a first electrical potential maintaining capacitor C2.

A control end of the fourth switch transistor T4 is connected to the input end of the second switch transistor T2, an input end of the fourth switch transistor T4 is connected to an output end of the fifth switch transistor T5, and an output end of the fourth switch transistor T4 is connected to the output end of the first switch transistor T1.

A control end of the fifth switch transistor T5 is connected to an output end of the seventh switch transistor T7, and an input end of the fifth switch transistor T5 is connected to the constant high-level voltage source.

A control end of the sixth switch transistor T6 is connected to the output end of the first switch transistor T1, an input end of the sixth switch transistor T6 is connected to the

constant high-level voltage source, and an output end of the sixth switch transistor **T6** is connected to an output end of the seventh switch transistor **T7**.

A control end of the seventh switch transistor **T7** inputs a second clock signal **XCK**, an input end of the seventh switch transistor **T7** is connected to the constant low-level voltage source, and the output end of the seventh switch transistor **T7** is connected to the control end of the third switch transistor **T3**.

One end of the first electrical potential maintaining capacitor **C2** is connected to the constant high-level voltage source, and the other end of the first electrical potential maintaining capacitor **C2** is connected to the output end of the seventh switch transistor **T7**.

The first clock signal **CK** and the second clock signal **XCK** are reverse clock impulse signals.

The bootstrap capacitor **C1** is set up between the output end of the first switch transistor **T1** and the output end of the second switch transistor **T2** of the pull-down module **22**.

Referring to FIG. 2 and FIG. 3, FIG. 3 is a signal waveform diagram of a scan driving circuit according to the first preferred embodiment of the present invention. All the switch transistors of the present preferred embodiment are PMOS type transistors. When the scan driving circuit **20** of the present preferred embodiment is operated and the previous-level scan signal **G(N-1)** is turned into a low-level signal, the first clock signal **CK** is a high-level signal, the second clock signal **XCK** is a low-level signal, the first switch transistor **T1** is turned on, and the low-level scan signal **U2D** outputs to the control end of the second switch transistor **T2** through the first switch transistor **T1**, so as to pull down the scan level signal **Q(N)** of the scan line. Therefore, the second switch transistor **T2** is turned on. However, due to the first clock signal **CK** being a high-level signal, the scan signal **G(N)** is still a high-level signal. At the same time, the sixth switch transistor **T6** is turned on, the third switch transistor **T3** and the fifth switch transistor **T5** are turned off through a high-level signal **VGH**, and the fourth switch transistor **T4** is turned off through the first clock signal **CK**.

Afterwards, the previous-level scan signal **G(N-1)** is turned into a high-level signal, the first clock signal **CK** is turned into a low-level signal, the second clock signal **XCK** is turned into a high-level signal, the first switch transistor **T1** is turned off, and the second switch transistor **T2** is still turned on under the effect of the bootstrap capacitor **C1**, so as to the scan signal **G(N)** is turned into a low-level signal under the effect of the first clock signal **CK** through the second switch transistor **T2**. The electrical potential of the scan level signal **Q(N)** of the scan line is pulled down under the effect of the scan signal **G(N)** and the bootstrap capacitor **C1**, so as to let the electrical potential of the scan level signal **Q(N)** to be lower. At this time, since the sixth switch transistor **T6** is turned on, the third switch transistor **T3** and the fifth switch transistor **T5** are still turned off under the effect of the high-level signal **VGH**, and the fourth switch transistor **T4** is turned on under the effect of the first clock signal **CK**.

Then, the first clock signal **CK** is turned into a high-level signal, and the second clock signal **XCK** is turned into a low-level signal; at this time, the seventh switch transistor **T7** is turned on under the effect of the second clock signal, and the third switch transistor **T3** and the fifth switch transistor **T5** are turned on under the effect of the low-level signal **VGL**; and the scan signal **G(N)** is pulled up by the high-level signal **HGL** through the third switch transistor **T3**, and the scan level signal **Q(N)** of the scan line is pulled up

through the bootstrap capacitor **C1**. The fourth switch transistor is turned off under the effect of the first clock signal **CK**, and the first switch transistor **T1** is turned off under the effect of the previous-level scan signal **G(N-1)**. Therefore, the scan level signal **Q(N)** of the scan line can be kept in a high-level, so as to keep the scan signal **G(N)** in a high-level.

Afterwards, the first clock signal is turned into a low-level signal, and the second clock signal is turned into a high-level signal; at this time, the fourth switch transistor **T4** is turned on under the effect of the first clock signal **CK**, and the fifth switch transistor **T5** is also turned on under the effect of the first electrical potential maintaining capacitor **C2**. The scan level signal **Q(N)** of the scan line can kept in a high-level by receiving the high-level signal **VGH** through the fourth switch transistor **T4** and the fifth switch transistor **T5**, and the scan signal **G(N)** is also kept in a high-level.

The scan level signal **Q(N)** of the scan line and the scan signal **G(N)** are always kept in a high-level (through the third switch transistor **T3** or the fourth switch transistor **T4** and the fifth switch transistor **T5**). Until the first switch transistor is turned on, the scan level signal **Q(N)** of the scan line and the scan signal **G(N)** are turned into a low-level through the low-level scan signal **U2D**.

The driving operation for the cascaded scan lines of the scan driving circuit **20** of the present preferred embodiment is thus implemented.

The scan driving circuit of the present invention uses a PMOS type transistor to control every module, so as to let the scan driving circuit to have a simple overall structure and lower energy consumption.

Refer to FIG. 4, which is a structural diagram of a scan driving circuit according to the second preferred embodiment of the present invention. On the basis of the first preferred embodiment, the pull-up maintaining module **44** of the scan driving circuit **40** of the present preferred embodiment further comprises a second electrical potential maintaining capacitor **C3**. One end of the second electrical potential maintaining capacitor **C3** is connected to the constant high-level voltage source, and the other end of the second electrical potential maintaining capacitor **C3** is connected to the output end of the first switch transistor **T1**.

The configuration of the second electrical potential maintaining capacitor **C3** avoids the electrical leakage phenomenon of the scan level signal **Q(N)** through other switch transistors. Therefore, the scan signal **Q(N)** can be kept in a high-level through the second electrical potential maintaining capacitor **C3** and the high level signal **HGL**.

Refer to FIG. 5, which is a structural diagram of a scan driving circuit according to the third preferred embodiment of the present invention. On the basis of the first preferred embodiment, the pull-down control module **51** of the scan driving circuit **50** further comprises an eighth switch transistor **T8**. A control end of the eighth switch transistor **T8** inputs a next-level scan signal **G(N+1)**, an input end of the eighth switch transistor **T8** inputs a low-level scan signal **D2U**, and an output end of the eighth switch transistor **T8** is connected to the pull-down module **22**, the pull-up maintaining module **24** and the bootstrap capacitor **C1** respectively.

The scan driving circuit **50** of the present preferred embodiment implements a reverse scanning operation through the eighth switch transistor **T8**, which pulls down a present-level scan signal **G(N)** though the next-level scan signal **G(N+1)**.

Refer to FIG. 6, which is a structural diagram of a scan driving circuit according to the fourth preferred embodiment of the present invention. On the basis of the first preferred

embodiment, the pull-down control module 61 of the scan driving circuit 60 of the present preferred embodiment comprises a first switch transistor T1, a ninth switch transistor T9 and the eighth switch transistor T8.

The control end of the first switch transistor T1 inputs a low-level scan signal U2D, the input end of the first switch transistor T1 inputs the previous-level scan signal G(N-1), and the output end of the first switch transistor T1 is connected to an input end of the ninth switch transistor T9. A control end of the ninth switch transistor T9 inputs a second clock signal XCK, and an output end of the ninth switch transistor T9 is connected to the pull-down module 22, the pull-up maintaining module 24 and the bootstrap capacitor C1 respectively. The second clock signal XCK and the first clock signal CK are reverse clock impulse signals. A control end of the eighth switch transistor T8 inputs a low-level scan signal D2U, an input end of the eighth switch transistor T8 inputs a next-level scan signal G(N+1), and an output end of the eighth switch transistor T8 is connected to an input end of the ninth switch transistor T9.

In the present preferred embodiment, the first switch transistor T1 and the ninth switch transistor T9 implement the operation of the first switch transistor T1 of the first preferred embodiment; and the eighth switch transistor T8 and the ninth switch transistor T9 implement the operation of the eighth switch transistor of the third preferred embodiment.

The specific working principles of the scan driving circuit of the present preferred embodiment are the same as or similar to the above first preferred embodiment and the third preferred embodiment. Please refer the specific details in the related descriptions of the first preferred embodiment and the third preferred embodiment.

The first switch transistor T1 and the eighth switch transistor T8 are always turned on, which ensures the stability of the output low-level signal of the pull-down control module.

The scan driving circuit of the present invention uses a PMOS type transistor to control every module, so as to let the scan driving circuit to have a simple overall structure and lower energy consumption, thus implementing a narrow border design of the corresponding liquid display device successfully. The present invention solves the problem of the existing scan driving circuit having a complex structure and higher energy consumption.

In summary, the present invention has been disclosed with preferred embodiments thereof, but the above described preferred embodiments are not intended to limit the present invention. Those who are skilled in the art can make many changes and modifications to the described embodiments which can be carried out without departing from the scope and the spirit of the invention that is intended to be limited only by the appended claims.

What is claimed is:

1. A scan driving circuit, executing a driving operation for cascaded scan lines, comprising:
  - a pull-down control module receiving a previous-level scan signal, and generating a low-level scan level signal corresponding to one of the scan lines according to the previous-level scan signal;
  - a pull-down module pulling down a scan signal of the corresponding scan line according to the scan level signal and a first clock signal;
  - a pull-up module pulling up the scan signal of the corresponding scan line according to a low-level signal and a high-level signal;

a pull-up maintaining module keeping the scan level signal of the corresponding scan line in a high-level according to the low-level signal and the high-level signal;

a bootstrap capacitor generating a low-level or a high-level of the scan level signal of the scan line; a constant low-level voltage source providing the low-level signal; and a constant high-level voltage source providing the high-level signal;

wherein the scan driving circuit uses a P-metal-oxide-semiconductor (PMOS) type transistor to control the pull-down control module, the pull-down module, the pull-up module and the pull-up maintaining module; wherein the pull-down control module includes a first switch transistor, a control end of the first switch transistor inputs the previous-level scan signal, an input end of the first switch transistor inputs a low-level scan signal, and an output end of the first switch transistor is connected to the pull-down module, the pull-up maintaining module and the bootstrap capacitor respectively;

wherein the pull-up maintaining module includes a second electrical potential maintaining capacitor, one end of the second electrical potential maintaining capacitor is connected to the constant high-level voltage source, and the other end of the second electrical potential maintaining capacitor is connected to the output end of the first switch transistor.

2. The scan driving circuit according to claim 1, wherein the pull-down module comprises a second switch transistor, a control end of the second switch transistor is connected to the output end of the first switch transistor of the pull-down control module, an input end of the second switch transistor inputs a first clock signal, and an output end of the second switch transistor inputs a present-level scan signal.

3. The scan driving circuit according to claim 2, wherein the pull-up module comprises a third switch transistor, a control end of the third switch transistor is connected to the constant low-level voltage source, an input end of the third switch transistor is connected to the constant high-level voltage source, and an output end of the third switch transistor is connected to the output end of the second switch transistor.

4. The scan driving circuit according to claim 3, wherein the pull-up maintaining module further comprises a fourth switch transistor, a fifth switch transistor, a sixth switch transistor and a seventh switch transistor;

wherein a control end of the fourth switch transistor is connected to the input end of the second switch transistor, an input end of the fourth switch transistor is connected to an output end of the fifth switch transistor, and an output end of the fourth switch transistor is connected to the output end of the first switch transistor;

wherein a control end of the fifth switch transistor is connected to an output end of the seventh switch transistor, and an input end of the fifth switch transistor is connected to the constant high-level voltage source; wherein a control end of the sixth switch transistor is connected to the output end of the first switch transistor, an input end of the sixth switch transistor is connected to the constant high-level voltage source, and an output end of the sixth switch transistor is connected to an output end of the seventh switch transistor; wherein a control end of the seventh switch transistor inputs a second clock signal, an input end of the

11

seventh switch transistor is connected to the constant low-level voltage source, and the output end of the seventh switch transistor is connected to the control end of the third switch transistor.

5. The scan driving circuit according to claim 4, wherein the second clock signal and the first clock signal are reverse clock impulse signals.

6. The scan driving circuit according to claim 4, wherein the pull-down control module further comprises an eighth switch transistor, a control end of the eighth switch transistor inputs a next-level scan signal, an input end of the eighth switch transistor inputs a low-level scan signal, and an output end of the eighth switch transistor is connected to the pull-down module, the pull-up maintaining module and the bootstrap capacitor respectively.

7. The scan driving circuit according to claim 4, wherein the pull-up maintaining module further comprises a first electrical potential maintaining capacitor, one end of the first electrical potential maintaining capacitor is connected to the constant high-level voltage source, and the other end of the first electrical potential maintaining capacitor is connected to the output end of the seventh switch transistor.

8. The scan driving circuit according to claim 1, wherein the pull-down control module comprises a first switch transistor and a ninth switch transistor;

wherein the control end of the first switch transistor inputs a low-level scan signal, the input end of the first switch transistor inputs the previous-level scan signal, and the output end of the first switch transistor is connected to an input end of the ninth switch transistor;

wherein a control end of the ninth switch transistor inputs a second clock signal, and an output end of the ninth switch transistor is connected to the pull-down module, the pull-up maintaining module and the bootstrap capacitor respectively.

9. The scan driving circuit according to claim 1, wherein the second clock signal and the first clock signal are reverse clock impulse signals.

10. The scan driving circuit according to claim 1, wherein the pull-down control module further comprises an eighth switch transistor;

wherein a control end of the eighth switch transistor inputs a low-level scan signal, an input end of the eighth switch transistor inputs a next-level scan signal, and an output end of the eighth switch transistor is connected to an input end of the ninth switch transistor.

11. A scan driving circuit, executing a driving operation for cascaded scan lines, comprising:

a pull-down control module receiving a previous-level scan signal, and generating a low-level scan level signal corresponding to one of the scan lines according to the previous-level scan signal;

a pull-down module pulling down a scan signal of the corresponding scan line according to the scan level signal and a first clock signal;

a pull-up module pulling up the scan signal of the corresponding scan line according to a low-level signal and a high-level signal;

a pull-up maintaining module keeping the scan level signal of the corresponding scan line in a high-level according to the low-level signal and the high-level signal;

a bootstrap capacitor generating a low-level or a high-level of the scan level signal of the scan line; a constant low-level voltage source providing the low-level signal; and

12

a constant high-level voltage source providing the high-level signal;

wherein the scan driving circuit uses a P-metal-oxide-semiconductor (PMOS) type transistor to control the pull-down control module, the pull-down module, the pull-up module and the pull-up maintaining module.

12. The scan driving circuit according to claim 11, wherein the pull-down control module includes a first switch transistor, a control end of the first switch transistor inputs the previous-level scan signal, an input end of the first switch transistor inputs a low-level scan signal, and an output end of the first switch transistor is connected to the pull-down module, the pull-up maintaining module and the bootstrap capacitor respectively.

13. The scan driving circuit according to claim 12, wherein the pull-down module comprises a second switch transistor, a control end of the second switch transistor is connected to the output end of the first switch transistor of the pull-down control module, an input end of the second switch transistor inputs a first clock signal, and an output end of the second switch transistor inputs a present-level scan signal.

14. The scan driving circuit according to claim 13, wherein the pull-up module comprises a third switch transistor, a control end of the third switch transistor is connected to the constant low-level voltage source, an input end of the third switch transistor is connected to the constant high-level voltage source, and an output end of the third switch transistor is connected to the output end of the second switch transistor.

15. The scan driving circuit according to claim 14, wherein the pull-up maintaining module further comprises a fourth switch transistor, a fifth switch transistor, a sixth switch transistor and a seventh switch transistor;

wherein a control end of the fourth switch transistor is connected to the input end of the second switch transistor, an input end of the fourth switch transistor is connected to an output end of the fifth switch transistor, and an output end of the fourth switch transistor is connected to the output end of the first switch transistor;

wherein a control end of the fifth switch transistor is connected to an output end of the seventh switch transistor, and an input end of the fifth switch transistor is connected to the constant high-level voltage source; wherein a control end of the sixth switch transistor is connected to the output end of the first switch transistor, an input end of the sixth switch transistor is connected to the constant high-level voltage source, and an output end of the sixth switch transistor is connected to an output end of the seventh switch transistor;

wherein a control end of the seventh switch transistor inputs a second clock signal, an input end of the seventh switch transistor is connected to the constant low-level voltage source, and the output end of the seventh switch transistor is connected to the control end of the third switch transistor;

wherein the second clock signal and the first clock signal are reverse clock impulse signals.

16. The scan driving circuit according to claim 15, wherein the pull-down control module further comprises an eighth switch transistor, a control end of the eighth switch transistor inputs a next-level scan signal, an input end of the eighth switch transistor inputs a low-level scan signal, and an output end of the eighth switch transistor is connected to the pull-down module, the pull-up maintaining module and the bootstrap capacitor respectively.

13

17. The scan driving circuit according to claim 15, wherein the pull-up maintaining module further comprises a first electrical potential maintaining capacitor, one end of the first electrical potential maintaining capacitor is connected to the constant high-level voltage source, and the other end of the first electrical potential maintaining capacitor is connected to the output end of the seventh switch transistor.

18. The scan driving circuit according to claim 17, wherein the pull-up maintaining module includes a second electrical potential maintaining capacitor, one end of the second electrical potential maintaining capacitor is connected to the constant high-level voltage source, and the other end of the second electrical potential maintaining capacitor is connected to the output end of the first switch transistor.

19. The scan driving circuit according to claim 11, wherein the pull-down control module comprises a first switch transistor and a ninth switch transistor;

wherein the control end of the first switch transistor inputs a low-level scan signal, the input end of the first switch

5

10

15

14

transistor inputs the previous-level scan signal, and the output end of the first switch transistor is connected to an input end of the ninth switch transistor; wherein a control end of the ninth switch transistor inputs a second clock signal, and an output end of the ninth switch transistor is connected to the pull-down module, the pull-up maintaining module and the bootstrap capacitor respectively;

wherein the second clock signal and the first clock signal are reverse clock impulse signals.

20. The scan driving circuit according to claim 19, wherein the pull-down control module further comprises an eighth switch transistor;

wherein a control end of the eighth switch transistor inputs a low-level scan signal, an input end of the eighth switch transistor inputs a next-level scan signal, and an output end of the eighth switch transistor is connected to the input end of the ninth switch transistor.
